Geo. P. Kimmel.
Attorney

UNITED STATES PATENT OFFICE.

OSCAR J. MESNA, OF PELICAN RAPIDS, MINNESOTA.

VALVE.

1,295,999.

Specification of Letters Patent.

Patented Mar. 4, 1919.

Application filed January 6, 1917. Serial No. 140,952.

To all whom it may concern:

Be it known that I, OSCAR J. MESNA, a citizen of the United States, and resident of Pelican Rapids, in the county of Otter Tail and State of Minnesota, have invented certain new and useful Improvements in Valves, of which the following is a specification.

This invention relates to valves and the 10 invention has more especial reference to an improved multiple-way valve.

The invention has for its principal object to provide a multiple way valve especially adapted for use in connection with the 15 exhaust manifold of motor driven vehicles, whereby, passage of the spent gases from the engine or motor through the exhaust manifold may be varied at will by the operator, in order that the same may be directed 20 into an exhaust operated signal, which signals are usually carried by or in proximity of the exhaust manifold, or to the engine muffler, or directly through the exhaust cut-out, whereby, to accelerate the speed of the 25 engine.

As an object of equal importance, the invention aims to provide a novel form of casing for receiving the multiple way valves, the same having a plurality of ports there- 30 in adapted for registration with the ways of the valve and also being provided with coupling means so as to readily permit the connecting of the casing ports to the device for receiving the spent gases therefrom.

Among other aims and objects of the invention to be recited, the provision of a valve of the character mentioned, with a view to compactness, and in which the number of parts are few, the construction sim- 35 ple, cost of production small, and efficiency and operation high.

All of the foregoing together with additional advantageous details and arrangements of the parts of the preferred embodiment of my invention will be clear from the specific description hereinafter contained, when read in connection with the accompanying drawings forming a part thereof, wherein the preferred embodiment of the 40 invention is illustrated for the purpose of facilitating a clear understanding of the present improvements.

In the drawings:

Figure 1 is a horizontal section in eleva- 45 tion of my improved multiple way valve;

Fig. 2 is a side elevation of the same, a

portion of the casing being broken away and shown in section; and

Fig. 3 is a fragmental detail in top plan of the valve receiving chamber the closure 90 plate removed therefrom and showing means for fastening said closure plate thereto.

Referring now more specifically to the drawings, and in connection with which like reference characters will refer to the same 65 parts in the several views, my improved multiple way valve in its preferred embodiment comprises an annular valve receiving chamber or casing 1, the said casing being provided with spaced apart radially disposed ports 2, the said ports having necks 3 extending therefrom, in order that the same may be connected with the various devices which are to receive the spent gases from the exhaust manifold of the engine. Set 70

75 screws 4 are arranged in suitably screw threaded openings formed in the outer extremities of the coupling necks 3, and obviously, provide means for securing such devices as may be engaged therewith. A con- 80

centrically disposed bearing pocket 5 is ar- 85 ranged in the bottom of the casing 1 and serves as means for rotatably receiving the bearing pintle of the multiple way valve, which will be hereinafter more fully de- 90

scribed. To provide means whereby a cover plate 6 may be arranged over the open upper end of the casing 1 and secured thereto, apertured ears 7 are formed integral with the upper marginal edges of the said casing 95 to point adjacent the jointure of the coupling neck 3 with the same. Similar aper- 100 tured ears 8 are formed upon the peripheral edge of the closure plate 6, which obviously, is of a shape complementary to the shape of the casing 1, and, when alined with the ears 95

105 7, are adapted to receive set screws 9, or other suitable fastening devices, therethrough. The annular closure plate 6 is provided with a concentrically arranged bearing opening 100

110, it being noted, that the said bearing opening is in direct vertical alinement with the pocket 5 as formed in the casing bottom. Referring now to the novel cut off means 105

or valve, the same includes a disk like body 11, which body is of a size to permit the snug reception thereof within the casing 1 and has formed upon the upper and lower faces, concentrically arranged bearing pintles 12, which pintles are adapted to be received 110 by the bearing pockets 5 and bearing open- 115

ing 10, the upper bearing pintle 12, having

a squared shank or extension 13 formed thereon whereby an arm 14 which is provided with a corresponding opening in one end thereof may be arranged over the same.

5 A set screw 15 is carried by the adjacent extremity of the arm 14 and by turning the same inwardly into engagement with the adjacent portion of the shank 13, it will be appreciated, that said arm will be securely held in position. A second annular opening is formed upon the remaining extremity of the arm 14 and has alined therewith, a similar opening formed within one end of a connecting rod 16, thus, permitting the insertion of a locking bolt 17. It is to be understood, that the connecting rod 16 extends to a point upon the vehicle in proximity of the operator thereof, whereby, the same may be readily engaged so as to cause 20 rotation of the valve 11 in the desired direction. Furthermore, the connecting rod 16, may be and preferably is engaged with a foot lever supported by the flooring of the vehicle. By so connecting the rod 16, operation of the same may be readily effected. A plurality of longitudinally extending annular ways 18, 19 and 20 are arranged within the valve body 11, the way 19, preferably, extending through the middle thereof, with 25 the ways 18 and 20 arranged upon either side of the same. Attention is directed to the fact, that the way 19 extends straight through the valve body 11, thus, permitting the direct passage of the spent gases from 30 the exhaust manifold of the engine, through the oppositely disposed neck, it being evident, that one of the said coupling necks are engaged to the extremity of the exhaust manifold while the other is connected with 35 the engine muffler, but, the ways 18 and 20 are substantially arcuate and are curved in opposite directions, hence permitting the same to be engaged with the exhaust manifold engaging ports of the casing 1 and in 40 one of the right-angularly disposed ports, the coupling neck of which ports may be connected to an exhaust operated signal and the usual cut out pipe, the latter of course being provided as a means for permitting 45 the acceleration of the engine at times when the same is subjected to heavy pull.

In order that the ports 18 and 20 of the valve 11 will be alined with their respective ports formed in the casing 1, a horizontally disposed slot 21 is formed in one side of the casing, preferably in proximity of one of the ports 2 and receives therethrough a finger 22 carried on the valve 11. Hence, when the finger engages one end of 50 the slot 21 the port 18 will be in alinement with its respective point, and when the fin-

ger engages the opposite end of the slot the port 20 will be in alinement with its respective point. Thus, proper functioning of the valve and casing ports is insured.

65

From the foregoing, it will be appreciated by workers in the art, that I have provided a multiple way valve which may be readily attached to the free extremity of an exhaust manifold and when secured thereto will provide means whereby the passage of the spent gases from the exhaust manifold may be directed in any one of a number of devices as attached to and communicating with the improved valve, in order that the same may 70 properly perform their functions.

75

Although the device as herein described appears to be limited to its use in connection with the exhaust manifold of an engine, I desire to have it understood that the 80 valve may be used for various purposes, such as conditions or preference may dictate.

85

As hereinbefore indicated, I do not wish to be understood as confining the invention to the particular embodiments chosen 85 for illustration herein, nor to the exact construction, arrangement and adaptation of the parts shown and described, but I reserve the right to make any changes and alterations that fairly fall within the spirit and scope 90 of the invention.

I claim:

In a device of the character described, an annular casing having a plurality of oppositely disposed ports formed in the side 95 walls thereof and a concentrically disposed bearing opening formed in its bottom, apertured ears formed integrally with the upper portion of the casing adjacent said oppositely disposed ports and the open top of 100 said casing, an annular cover having apertured ears formed thereon corresponding to said first mentioned apertured ears over the open top of the casing and connected thereto by fastening devices passing through the 105 alined apertured ears, a rotatable valve having a plurality of ways extending therethrough, one of said ways passing diametrically through the valve, while the remaining ways are curved to establish communication, 110 at times, between the relatively right angularly arranged ports in the casing, one portion of the side wall of said casing having a slot formed therein, a pin carried by the valve received in said slot for limiting rotary movement of the valve, and a handle 115 connected to said valve for facilitating rotation of the same.

In testimony whereof I affix my signature hereto.

OSCAR J. MESNA.
